[57] CLAIM

The ornamental design for a garment rack, as shown and described.

DESCRIPTION

FIG. 1 is a perspective view of a garment rack showing our new design;

FIG. 2 is a top plan view thereof;

FIG. 3 is a left side elevational view, the right side being identical thereto;

FIG. 4 is a front elevational view, the rear being identical thereto;

FIG. 5 is a perspective view of a second embodiment of a garment rack showing our new design;

FIG. 6 is a top plan view thereof;

FIG. 7 is a left side elevational view, the right side being identical thereto; and

FIG. 8 is a front elevational view, the rear being identical thereto.

FIG. 1

FIG. 2

FIG. 3

FIG. 4

FIG. 5

FIG. 7

FIG. 6

FIG. 8
